UNITED STATES PATENT OFFICE.

JAMES H. SCHOONMAKER, OF WINONA, MINNESOTA, ASSIGNOR TO
WINONA WIRE CABLE COMPANY, OF WINONA, MINNESOTA, A
CORPORATION.

CABLE-MAKING MACHINE.

SPECIFICATION forming part of Letters Patent No. 749,752, dated January 19, 1904.

Application filed October 19, 1903. Serial No. 177,681. (No model.)

To all whom it may concern:

Be it known that I, JAMES H. SCHOONMAKER, a citizen of the United States, residing at Winona, in the county of Winona and State of Minnesota, have invented certain new and useful Improvements in Cable-Making Machines; and I do hereby declare the following to be a full, clear, and exact description of the invention, such as will enable others skilled in the art to which it appertains to make and use the same.

This invention, which relates to the manufacture of cables, contemplates the provision of a simply and durably constructed machine adapted for employment in the manufacture of cables and the like of the different dimensions and varieties, including the copper or other covered type.

An object of the invention is the production of a cable or the like the strands of which are possessed of their original tensile strength by reason of the maintenance of their molecular formation throughout the operation of the machine whereby the strength of the cable is greatly increased over present cables of like dimensions, structure, and material.

Another object of the invention is the elimination from the assembled strands of all tendency to untwist and become separated by the provision of means for effecting the feeding of the several strands devoid of twist in the direction which creates the stated tendency whereby the necessity at present existing of tying the cable ends is dispensed with and buckling or kinking of the cable is completely avoided.

A further object of the invention in the manufacture of strip-covered-strand cables is to so control the twisting of the covered strands into the cable structure as to bring the seams of the strips innermost, whereby the appearance of the cable is greatly improved by reason of the apparent solidity of the several strands.

Other objects of the invention and resultant advantages possessed by the machine and its product are set forth in the following detailed description, in connection with which

reference is to be had to the accompanying drawings, illustrating the invention in its preferred form of embodiment, it being understood that various changes and modifications may be made therein without exceeding the scope of the concluding claims.

In the drawings, Figure 1 is a top plan view of a cable-making machine embodying my invention. Fig. 2 is an enlarged cross-section of the machine on line 2-2 of Fig. 1, the frame being omitted. Fig. 3 is an enlarged cross-section of the machine on line 3-3 of Fig. 1, the frame being omitted. Fig. 4 is an enlarged cross-section on line 4-4 of Fig. 1. Fig. 5 is an enlarged view of the delivery end of the machine. Fig. 6 is an enlarged side elevation, partly in section, of the delivery end of the machine. Fig. 7 is an enlarged sectional view of the die-box and finishing-die. Fig. 8 is an elevation of the finishing-die. Fig. 9 is an elevation of the initial die located in advance of the finishing-die. Fig. 10 is an elevation of a disk employed to properly guide the wires and covering-strips to the dies. Figs. 11, 12, and 13 are views of the dies for effecting the covering of the center strand. Fig. 14 is a sectional view of a strip-spool and tension device therefor. Fig. 15 is a view of a washer forming part of the tension device. Fig. 16 is a cross-sectional view of a covered strand previous to being twisted into the cable. Fig. 17 is a view of the strand after being twisted into the cable. Fig. 18 is a perspective view of a strand-feeder forming an attachment to the strand-twisting device.

Referring to the drawings by numerals, 12 designate the end bars of the frame of the machine, and 34 are the side bars, the frame being supported by legs 55. A shaft 6, which carries the moving parts, extends longitudinally of the frame, being journaled at its forward end in a box 7 on the bar 1 and at its rear end in a die-box 8, presently to be described. The shaft is of tubular form, and through it passes the center strand or core of the cable, which is fed in at the forward shaft end. The direction of feed of the center and

outlying strands being toward the delivery end of the machine, and thrust against the die-box 8 is relieved by the provision of a collar 9 on the forward end of the shaft, the collar 5 abutting against the journal-box 7. To prevent vibration of the shaft, there is provided a series of truss-rods 10 10, disposed equidistant about the shaft and secured at their ends to collars 11 12, adjustable on said shaft. The 10 rods are intermediately bent over the hub-rim of an equalizer, hereinafter described, and the threaded ends of the rods are passed through openings in flanges on the collars 11 12 to receive nuts 13 13, which when tightened give 15 the rods the requisite tension to properly stiffen the shaft. The shaft and parts carried thereby are rotated from a shaft 14, journaled in a box 15 on the bar 2 through the medium of two gear-wheels 16 17, respectively keyed 20 on said shafts 14 and 6. The shaft 14 is preferably connected by gearing or otherwise with the cable drawing and measuring drum, (not shown,) which gearing is changeable to increase or diminish the velocity of the drum 25 relative to the speed of the shaft 6, whereby to obtain cables with long or short twisted strands, as desired.

Keyed or otherwise secured to the shaft 6 is a wheel 18, carrying at its rim a plurality 30 of spools 19 19, containing wire either in the form of a single strand or a multiple-wire strand, dependent upon the type of cable to be made. Each spool is rotatably mounted in a forked bracket 20, which has a pin 21 loosely 35 passed through an opening in said rim and to the end of which is fixed an arm 22. The arms 22 are pivotally connected at their lower ends to a ring-weight 23, adjacent to the wheel 18, the function of which is to maintain the 40 spools vertically throughout their rotary traverse, whereby twisting of the strands is prevented. The ring-weight is freely suspended from the wheel by the arms, and to prevent vibration of the weight there is employed a 45 roller 24, Fig. 2, which is supported on the frame at 24' and is preferably positioned to slightly clear the inner surface of the ring, with the object of preventing contact and wear when the parts are revolving at a comparatively 50 low rate of speed, in which event practically no vibration occurs. Inasmuch as the parts are in practice revolved in the one direction—namely, from left to right—but one roller 24 is required to prevent vibration of the 55 ring. From the spools 19 the strands pass through openings 25 25, near the outer ends of arms 26 26, extending radially from a hub 27, keyed to the shaft 6. The openings 25 25 are equidistant from the center of the shaft, whereas 60 as in traversing their rotary path the spools 19 19 deliver the strands at varying distances from the shaft-center. The provision of the equalizer-arms 26 insures the proper spacing of the strands, however, regardless of the po-

sitions of the points of delivery from the 65 spools. The arms are threaded at their inner ends for insertion in threaded sockets in the hub 27, and 28 28 are nuts for locking the arms in place. The strands pass from the equalizer to and through a circular series of 70 openings 29 in a disk 30, keyed on the shaft 6 and located in front of the gear-wheel 17. The function of this disk is to concentrate and properly space the strands, as well as the strand-covering strips presently to be described, which strips pass through radially-disposed slots 31, alternating with the holes 29. Leaving the disk 30 the strands and strips pass between the spokes of the gear-wheel 17 and to and through a guiding-disk 80 32, screwed on a threaded portion of the shaft 6, said guiding-disk being relatively smaller than the disk 30 and having strand-holes 33 33 and radially-disposed strip-slots 34 34 alternating with said holes, the holes and slots being 85 inclined relatively to the axis of the shaft 6, as shown in Figs. 6 and 10.

The shaft 6 carries at its delivery end two die-disks 35 36, respectively provided with circular series of tapered die-holes 37 38, 90 through which the strands, whether covered or uncovered, are drawn, the holes 38 being of relatively smaller diameter than the holes 37. The disk 30 and die-disks 35 36 are screwed upon the shaft at threaded portions 95 of the latter, said threaded portions increasing in diameter from the end of the shaft, as will be understood. In the manufacture of cables formed of uncovered strands the die-disks 35 36 serve as guides for the strands, 100 being screwed tightly on the shaft to revolve therewith, and the die-disk 36 performs the further function of twisting the strands upon the center strand to form the cable. The die-disk 36 has its bearing in the die-box 8, being 105 confined at one end therein by an annular flange 39, which may be integral with the rear end of the die-box. Said flange cooperates with the collar 9 on the forward end of the shaft to resist the end thrust of the latter. The die-box 110 thus serves, through the medium of the die-disk 36, as the journal-bearing for the rear end of the shaft, and to permit a slight lateral movement of the latter, for a purpose presently to be explained, the die-box is supported on the 115 frame to be capable of a like movement, this being accomplished by the rack-and-pinion means shown in Fig. 6, 40 being the rack, carried by the die-box, and 41 being the pinion, which is rotated by a hand-crank 42. Bolts 43 serve to hold the box and shaft in their normal 120 position, the bolts being loosened previous to the movement of the box. The twisting of the strands to form the cable can be accomplished directly from the die-disk 36, or I 125 may employ the strand feeding and spacing device shown in Figs. 6 and 18, and which consists of a tube 44, having a threaded in-

ner end 45, insertible in the opening of the shaft 6 and of a tapering enlargement beyond said inner end, the line of taper conforming approximately to the inclination of the strands previous to being twisted into cable form. Near the outer end of the tube is an annular flange 46, in which is a circular series of holes 47, through which the strands are drawn, said holes serving to guide and properly space the strands immediately before the twisting operation.

In the manufacture of covered-strand cables there is fed through the shaft 6 a center strand, preferably covered with a strip of copper or the like, and to effect the said covering or inclosing of the center strand I employ the three dies 48 49 50. (Shown in Figs. 1, 11, 12, and 13.) The dies are supported on an extension 51 of the frame and rest against shoulders 52 52. In the die 48 is a relatively large converging opening 53, through which is drawn the center strand and strip, the opening being of the proper size to give a slight bend to the strip, and from said opening the strand and strip pass to and through converging openings 54 and 55, respectively provided in the dies 49 and 50. The die-openings 53, 54, and 55 diminish in diameter, as shown, the diameter of the finishing-opening 55 being approximately that of the covered strand. Preferably each of the intermediate and finishing dies 49 and 50 is provided with a series of different-sized die openings or holes, whereby it may be employed for various sizes of strands, the die being shiftable laterally to bring the proper hole in alinement with the shaft-aperture.

The strips for covering the outlying strands are fed from spools 56 56, revolvably supported on the ends of arms 57 57, extending radially from a hub 58, keyed to the shaft 6 adjacent to the equalizer. The spools 56, as well as the spools 19, are each provided with a tension device, preferably of the form shown in Figs. 14 and 15, the tension-nut 59 being held from rotation with the spool by an interposed washer 60, which has a bar 61 extending across the opening for the axle-pin 62 and engaging a slot 63 in said pin. As a further safeguard against the loosening of the nut 59 a set-screw 59' is employed. The strips are drawn from the spools 56 through the slots in the disks 30 32 and pass from thence through the die-disks 35 and 36. The holes 37 of the disk 35 are of relatively larger diameter than the holes 38 of the finishing-disk 36, and in the passage of a strand and strip successively through the holes 37 and 38 the converging walls of said holes act to bend the strip about the strand to completely cover the latter. The slots and holes of the disk 32 are so disposed relatively to the positions of the holes in the die-disks 35 and 36 as to bring the seam of the inclosing strip to a point away from the position it will occupy in the com-

pleted cable. By reference to Fig. 16 it will be seen that the seam of the strip 64 is positioned one quarter-turn to the right, whereas in the operation of twisting the strand 65 onto the center strand 66 the strand 65 is given approximately one quarter-turn, which brings the seam innermost, as shown in Fig. 17. By this operation the seams of the strip are concealed, and the cable has the appearance of being constructed from solid copper strands.

In operation if a cable composed of uncovered center and outlying strands is to be constructed a center strand-spool (not shown) is placed in position to feed the strand through the shaft-aperture, and a number of strand-carrying spools 19, corresponding to the desired number of outlying strands of the cable, are mounted in their respective brackets 20, the spools being disposed as equidistantly about the wheel 18 as possible where an odd number of strands are fed, and in this connection it will be understood that no limit is placed upon the number of spool-brackets to be employed, the number shown being merely for the purpose of illustration. The provision of the tension devices insures the feeding of the strands at an equal tension, whereby the complete cable is rendered very compact, the strands lying closely one against the other. The strands may each consist of a single wire or a number of wires twisted together, and the single or multiple wire strand may be covered or uncovered. The machine is therefore adapted not only for manufacturing all varieties and sizes of cables, but may also be employed in the making of the multiple-wire strands. In the construction of cables having strip-covered strands the requisite number of strip-spools are employed, and through the medium of the dies the strands, whether of single or multiple wire, are completely incased by the strip the seam of which is brought innermost, as previously stated. The longitudinal speed of the cable may vary relative to the rotation of the cable-forming parts, whereby a long or short twist is obtainable, or this modification of the length of twist may be effected by varying the speed of said parts. In constructing cables from strands of hard material, such as steel, it is advisable to give to the strands previous to their assemblage into cable form a slight twist, whereby the strands have a twisting tendency, which holds them closely together and prevents separation at the end. Assuming the direction of rotation of the machine to be from left to right viewed from the feeding end to give the strands the requisite twist, the gear-wheels 16 and 17 are disconnected by moving the die-box through the medium of the rack and pinion, and the longitudinal movement of the untwisted strands being checked the strand ends beyond the die-box are firmly held, and the shaft 6 and spools carried thereby are given by hand a few turns

from left to right, the turns giving to the strands the proper twist beyond the die-box, after which the gear-wheels are brought in mesh and the machine set in motion. This twist is maintained throughout the operation of the machine, the extent of the twist being governed by the degree of hardness of the material. Cables so made may be cut at any point without the necessity of previously wrapping or tying the cable, thereby facilitating the work of the lineman or other operator and effecting economy in the use of the cable. By the provision of the means for preventing a twist in the strands in the rotation of the wheel the original molecular formation of the strands is preserved, and the strength of the cable is unimpaired, and all tendency to buckling or kinking is avoided. In the stated direction of rotation of the parts the strands receive in their assemblage into cable form a right-hand twist, whereas without the means for preserving the vertical position of the spools the strands would receive a twist opposite to the direction of rotation of the parts. The elimination of this left-hand twist destroys all tendency of the cable-strands to untwist, and, moreover, as above stated, the molecular formation of the strands is preserved. Relatively soft strands are practically devoid of twist, and in relatively hard strands the slight twist for the purpose of preventing separation is insufficient to materially modify the molecular condition and strength of the strands.

I claim as my invention—

1. In a machine of the class described, the combination of a shaft, means for rotating said shaft, a wheel on the shaft, spool-carrying brackets mounted on said wheel, a freely-suspended ring-weight having arm connection with each of said brackets, and a roller out of contact with the weight during low speed of the machine, but contacting therewith during high speed for preventing vibration of the weight.

2. In a machine of the class described, the combination of a tubular shaft, adjustable truss-rods for stiffening said shaft, means for rotating the shaft, a wheel on the shaft, spool-carrying brackets on the wheel, means connected with the brackets for maintaining the spools in vertical position, adjustable tension devices carried by said brackets, and strand-spacing separately-secured arms extending radially from the shaft and having holes for the passage of the strands.

3. In a machine of the class described, the combination of a tubular shaft, a bearing for one end of the shaft, a disk on the other end of the shaft, a box in which said disk is rotatably confined said box being laterally movable relatively to the shaft-axis, means for rotating the shaft including two gear-wheels one carried by the shaft and means permitting the

moving of the box and shaft end to disengage the gear-wheels for the purpose hereinbefore described.

4. In a machine of the class described, the combination of a tubular shaft, a bearing for one end of the shaft, a disk on the other end of the shaft, a box in which said disk is rotatably confined said box being movable to effect lateral movement of the shaft end, means for moving said box, means for securing the box in normal position, and means for rotating the shaft including two gear-wheels one on said shaft.

5. In a machine of the class described, the combination of a tubular shaft for the passage of a center strand, a plurality of spools carried by the shaft for supplying outlying strands, tension-equalizing means for said strands, strand-covering-strip spools carried by said shaft, means for concentrating and positioning the strands and strips, and dies on the shaft effecting the covering of the strands by said strips.

6. In a machine of the class described, the combination of a tubular shaft for the passage of a center strand, a plurality of spools carried by the shaft for supplying outlying strands, tension-equalizing means for said strands, strand-covering-strip spools carried by said shaft, a disk on the shaft having strand-holes and strip-slots said disk serving to concentrate and position the strands and strips, a strand and strip guiding disk on the shaft to the rear of the aforesaid disk, and two die-disks on the shaft effecting the covering of the strands by said strips one of said disks constituting the finishing-die, and a die-box in which said finishing-die is rotatably confined.

7. In a machine of the class described, the combination of a tubular shaft for the passage of a strip-covered center strand, dies at the front of the shaft for effecting such covering, a plurality of outlying strand-spools carried by the shaft, tension-equalizers for said strands, strand-covering-strip spools carried by said shaft, a disk on the shaft having strand-holes and strip-slots said disk serving to concentrate and position the strands and strips, a strand and strip guiding disk on the shaft to the rear of the aforesaid disk, and two die-disks on the shaft effecting the covering of the strands by said strips one of said disks constituting the finishing-die, and a die-box in which said finishing-die is rotatably confined.

8. In a machine of the class described, the combination of means for feeding center and outlying strands and covering-strips for the outlying strands including a tubular shaft, dies carried by the shaft for effecting the covering of the strands by said strips, and a disk on the shaft in advance of the dies said disk having strand-openings and strip-slots and arranged with reference to the die-openings to

bring the strip-covering seams in position to be subsequently twisted innermost in the formation of the cable.

9. In a machine of the class described, the combination with the center and outlying strand-feeding means and strip-feeding means, of means effecting the covering of the strands by the strips, and means for twisting the cov-

ered strands into a cable with the strip-seams innermost.

In testimony whereof I affix my signature in presence of two witnesses.

JAMES H. SCHOONMAKER.
